UNITED STATES PATENT OFFICE

JOHN W. WARREN, OF ELK CITY, OKLAHOMA

TOILET CABINET

Application filed September 5, 1928. Serial No. 304,051.

The present invention is directed to improvements in toilet cabinets.

The primary object of the invention is to provide a device of this character so constructed that it can be conveniently secured to a wall for supporting various toilet articles.

Another object of the invention is to provide a cabinet of this nature which is simple in construction and so arranged that toilet articles, such as brushes and combs, soap, tumblers, tooth brushes, towels and other toilet articles can be supported for convenient access.

Another object of the invention is to provide a device of this character which is formed wholly from sheet metal.

With these and other objects in view, this invention resides in the novel features of construction, formation, combination and arrangement of parts to be hereinafter more fully described, claimed, and illustrated in the accompanying drawings, in which:—

Figure 1 is a perspective view of the device.

Figure 2 is a sectional view on line 2—2 of Figure 1.

Figure 3 is a sectional view on line 3—3 of Figure 1.

Figure 4 is a sectional view on line 4—4 of Figure 1.

Figure 5 is a sectional view on line 5—5 of Figure 2.

Figure 6 is a sectional view on line 6—6 of Figure 2.

The cabinet consists of spaced sides 1, the rear edges thereof terminating in flanges 2 through which securing devices are passed for supporting the cabinet upon a wall. The lower ends of the sides terminate in forwardly directed extensions 3, the lower edges of which are provided with inturned horizontal flanges 3'.

A shelf 4 is employed and has fixed longitudinally thereunder a bar 5, the ends of which terminate in trunnions 6 for rotatably engaging the bearings 7 formed in the sides 1, the shelf, when in its operative position resting upon the flanges 3'.

An elongated tray 8 is arranged between

the sides 1 and has its end walls 9 secured by rivets to the sides. The front wall 10 of the tray has secured thereto a resilient clamp 11 adapted to engage the forward edge of the shelf 4 when the same is swung upwardly, as shown in dotted lines in Figure 3 of the drawings.

Arranged above the tray 8 is a strip 12, the end flanges 13 of which are secured to the sides 1. Fixed to the central portion of the strip is a resilient sheet metal arm 14 having a plurality of seats 15 formed therein, the purpose of which will be later explained. Fixed to the upper ends of the sides 1 are the horizontally disposed plates 16, the inner ends of which terminate in vertical plates 17 which have their lower ends fixed to the shelf 12 in spaced relation. By providing the plates 16 and 17 compartments 18 are formed in which tooth brush holders, drinking glasses, shaving mugs, and the like can be conveniently placed therein, there being resilient clamps 19 carried by the plates 16 for supporting tooth brushes.

Supported by the opposed faces of the plates 17—17 are bearings 20 in which are engaged the pintles 21 carried by the ends of the mirror 22. It will, of course, be understood that, if desired, the mirror may be supported in a frame, and the trunnions fixed to the frame. Obviously, the mirror can be held in various inclined positions upon engaging the lower edge thereof in selected seats 15 of the arm 14.

Hooks 23 are secured to the sides 1 adjacent the upper ends thereof and upon which may be suspended towels or wash cloths.

The tray is primarily designed for holding soap, brushes and combs, while the shelf 4 may be used for supporting various toilet articles when being used, and since the shelf can be swung upwardly when not in use, a person can stand close to the mirror.

From the foregoing, it is thought that the construction, operation and many advantages of the herein described invention will be apparent to those skilled in the art, without further description, and it will be understood that various changes in the size, shape, and proportion and minor details of

construction may be resorted to without departing from the spirit or sacrificing any of the advantages of the invention.

What is claimed is:

- 5 1. A cabinet of the class described comprising spaced sides, a strip supported between the sides, horizontal plates fixed to the sides, vertical plates secured to the horizontal plates and to the strips and defining compartments, a mirror pivotally supported by the vertical plates, and means carried by the strip for holding the mirror in various adjusted positions.
- 10 2. A cabinet of the class described comprising a pair of sides, extensions carried by the sides, flanges on the extensions, a shelf pivotally supported between the extensions and normally engaged with the flanges to hold the shelf in its operative position, a tray supported by the sides, and a clasp carried by the tray for engaging the shelf to hold the same in its inoperative position.
- 15 3. A cabinet of the class described, comprising a pair of sides, a strip supported by and between the sides, horizontal and vertical plates secured, respectively, to the sides and strip and defining compartments, a resilient arm carried by the strip, a mirror pivotally supported by the vertical plates, and means carried by the arm for engagement with the mirror to hold the same in adjusted position.
- 20 4. A cabinet of the class described, comprising a pair of sides, a tray supported by and between the sides, a clasp carried by the tray, a shelf having a bar fixed thereto, means for pivotally connecting the ends of the bar to the sides, means carried by the sides for holding the shelf in a horizontal position, said shelf being adapted to engage the clasp to hold the same in its inoperative position.
- 25 5. A cabinet of the class described, comprising a pair of sides, a strip supported between the sides, plates secured to the sides and strips and defining compartments, a mirror pivotally supported between certain of the plates, a tray supported by the sides, a shelf pivotally supported by the sides and swingable upwardly to its inoperative position, and means carried by the tray for engaging the shelf to hold the same in its inoperative position.

In testimony whereof I affix my signature.

JOHN W. WARREN. [L.S.]
